ROTATABLE DEVICE

Philip A. Johnson, Van Nuys, Calif., assignor to
 Bendix Aviation Corporation, South Bend, Ind.,
 a corporation of Delaware

Application July 13, 1945, Serial No. 604,764

3 Claims. (Cl. 74—573)

1

This invention relates to rotatable devices and has as a broad object to provide a practicable rotatable structure that, when rotating, automatically shifts its center of gravity into alignment with its axis of rotation so that unbalance and resultant vibrations are prevented.

The invention is useful in a large field of rotatable devices where accurate balancing is desired and lends itself particularly to use in centrifugal drying devices, such as clothes dryers, in which it is impossible or impractical to symmetrically distribute the load about the axis of rotation.

Essentially the invention involves the addition to a rotatable structure of an annular liquid receptacle normally symmetrical with respect to the axis of rotation but automatically responsive to a lack of balance to distort in such direction as to concentrate the liquid on the side of the structure opposite the unbalanced weight.

The manner in which the foregoing object together with other more specific objects and features of the invention are achieved will be apparent from the detailed description to follow of certain specific embodiments thereof.

In the drawing:

Fig. 1 is a vertical section through a portion of a washing machine incorporating the invention, showing the elements in normal position.

Fig. 2 is a side view similar to Fig. 1 but showing the elements positioned to neutralize an unbalanced load.

Figs. 3, 4, 5 and 6 are vertical sections showing alternative structures in accordance with the invention.

Referring first to Fig. 1, there is shown the upper portion of a washing machine comprising an outer casing 10 containing a tub 11. There is positioned within the tub 11 a rotatable clothes basket 12. This clothes basket comprises an outer, open-top container having a cylindrical wall 13 and a flat bottom wall 14, which normally rests upon a flange 15 of a bushing 16, which extends through the bottom wall 17 of the tub. A drive shaft 18 extends through the bushing 16 and is connected at its upper end to an agitator 19, the agitator having at its lower end a sleeve bearing 20, which bears against the outer surface of the bushing 16.

During the washing operation, the agitator 19 is oscillated by the shaft 18, at which time the basket 12 remains substantially stationary by virtue of the fact that it is out of direct contact with the agitator and rests on the stationary flange 15 of the bushing 16. When the washing

2

operation is completed, the clothes are dried by elevating the shaft 18 and rotating it continuously in one direction. Elevation of the shaft causes an outwardly extending flange 21 on the agitator 19 to engage against an inwardly extending flange 22, secured to the bottom wall 14 of the basket, as by welding 23. The shaft 18 and agitator 19 are elevated sufficiently to lift the bottom wall 14 of the basket clear of the flange 15, as shown in Fig. 2.

As so far described, the structure is substantially in accordance with prior devices, which had the objectionable characteristic that unless the clothes were perfectly distributed within the basket 12 the latter would be unbalanced and would tend to vibrate when rotated.

In accordance with the present invention, unbalance and resultant vibration are prevented by providing the basket 12 with an inner peripheral wall 24, which is radially movable with respect to the wall 13, but is sealed with respect to the latter at the top and at the bottom to provide an annular chamber 25 adapted to confine a body of water or other balancing liquid. As shown in Fig. 1, the lower edge of the inner wall 24 is connected to the bottom wall 14 by an annular connecting wall 26 of rubber, and the upper edge of the inner wall 24 is connected to the upper edge of the wall 13 by an annular wall 27 of rubber. The lower edge of the inner wall 24 is preferably turned in to form a flat lip 28 adapted to rest upon the rubber wall 26. The inner edge of the rubber wall 26 is sealed to the bottom wall 14 by clamping it between the bottom wall and the outer edge of the flange member 22. The outer edge of the rubber wall 28 is sealed to the wall 24 by a clamping ring 29 riveted to the wall 24. The rubber wall 27 is likewise sealed to the upper edges of the walls 24 and 13 by riveted clamping rings 30 and 31 respectively.

The space 25 is completely filled with water or other balancing liquid, and, when the basket is spinning, the inner wall 24 is shifted by the centrifugal force of an unbalanced load, to concentrate the water on the side of the axis opposite to the center of gravity of the load. Thus, as shown in Fig. 2, a load of clothes 32 within the basket is shown unevenly distributed, with the clothes concentrated in the left side of the basket as it appears in the drawing. During rotation, the centrifugal force developed in the clothes is therefore unbalanced, and causes the inner wall member 24 to shift, with respect to the outer wall 13, to the left as shown in Fig. 2.

This brings the inner wall 24 closer to the outer wall 13 at the point where the clothes are massed, and causes the walls 24 and 13 to separate at the diametrically opposite point. Water in the space 25 is therefore displaced from the point adjacent the greater mass of clothes to the diametrically opposite point, as clearly shown in Fig. 2.

It is found in practice that the inner wall 24 moves just sufficiently to effect a shift in the distribution of the water in the space 25 necessary to compensate for the unbalance of the clothes load. If the unbalance of the clothes load is very slight, only a slight corrective movement of the inner wall occurs, whereas, if the unbalance resulting from the equal distribution of the clothes is large, the corrective movement of the inner wall 24 is correspondingly greater.

The movement of the inner wall 24 out of concentric relation is limited, because any portion of the wall 24 that is closer to the wall 13 than another portion of the wall 24 is exposed to a greater water pressure. Thus, the pressure developed in the water 24, due to centrifugal force, increases as the wall 13 is approached, the same as the pressure increases with depth in a stationary body of water. Furthermore, at the speeds of rotation ordinarily employed in devices of this type, the centrifugal forces developed in the water 25 are much greater than the force of gravity, so that the pressure increases relatively rapidly as the wall 13 is approached. Therefore, relatively small movement of the wall 24 out of concentric relation to the outer wall materially reduces the pressure acting on that portion of the wall closest to the axis of rotation and increases the water pressure acting against the diametrically opposite portion of the wall.

During normal operation, the basket is accelerated slowly during the spinning operation, and the inner wall 24 shifts gradually into its ultimate position as the centrifugal forces resulting from rotation increase. However, the structure is capable of reacting quickly to an unbalanced condition. Thus it is found that if the basket is brought up to speed while empty, and a mass of clothes is then thrown into the basket while it is rotating, the wall 24 is moved immediately into a new position sufficient to compensate for the unbalanced clothes load, and even momentary vibration of the device is substantially prevented.

As shown in Fig. 1, the inner wall 24 is tapered from small diameter at the bottom to a larger diameter at the top, and water extracted from the clothes by the spinning action is directed upwardly along the wall 24 and over the top thereof by the centrifugal force. The water then impinges against the wall 11 of the tub and runs to the bottom where it may be drained off through a suitable drain cock 33.

The schematic diagram of Fig. 3 shows a modification of the structure of Fig. 1, in which the space 25a containing the balancing liquid is defined by an annular flexible container 35 of rubber or the like, which fits between the inner wall 24a and the outer wall 13a of the basket. This construction eliminates the sealing walls 26 and 27 of Fig. 1. The device operates in the same general manner as that of Fig. 1.

An important advantage of my structure is that it instantly responds to any change in the unbalance in either direction. Thus in the case of a clothes centrifuge the unbalanced load becomes progressively less as the water is extracted,

and the inner wall 24 gradually moves back toward concentric relation with the wall 13, to maintain the proper distribution of the balancing liquid to just balance the clothes load at all times.

Fig. 4 shows schematically another arrangement whereby the invention may be employed without the use of sealing walls, in a device from which liquid does not have to be drained. Thus in this instance there is provided an outer rotatable container 40 having a cylindrical outer wall 41, a flat bottom wall 42, and an annular flat top wall 43 extending inwardly from the cylindrical wall 41. There is contained within the outer container 40, an inner container 44 having a cylindrical wall 45, and flat annular bottom and top walls 46 and 47, respectively. The bottom wall 42 of the outer container 40 is secured to and rotated by a drive shaft 48, supported in a bearing 49. (The inner container 44 rests in sliding relation on the bottom wall 42 of the outer container.)

The annular space between the cylindrical walls 45 and 41 and between the bottom walls 46 and 42 contains a liquid, such as water, in amount such as to completely fill the space between the cylindrical walls 45 and 41 when the device is rotating, as shown in Fig. 4. However, the amount is not great enough to cause it to leak out between the walls 47 and 43. If it is not loaded, or if there is a balanced load within the container 44, the latter will remain coaxial with the outer container 40. On the other hand, if there is an unbalanced load in the container 44, the latter will shift laterally to displace water to a diametrically opposite point and restore the balance, the same as in the arrangement of Fig. 1.

It is to be understood that the invention is not limited to use as a centrifuge. Thus, in the arrangement of Fig. 4, for example, the container 44 might just as well be a solid body, and the structure can be used as a flywheel or gyroscope which will be self-balancing at high speeds and thereby eliminate need of extremely accurate machining and balancing during manufacture.

Two variations of the structure previously described are disclosed in Figs. 5 and 6. In the previously described modifications, the inner rotating member moved bodily to compensate for unbalance. In the modification of Figs. 5 and 6 the rotating basket is pivotally supported near the top so as to swing at the bottom and displace the balancing liquid.

Referring first to Fig. 5, there is shown a rotatable basket 55 having tapered inner and outer walls 56 and 57, interconnected by a bottom wall 58 to define an annular trough in which material to be centrifuged is placed. The basket is supported for rotation by a shaft 59, the shaft being supported in a stationary bearing 60. The upper end of the shaft 59 is connected to the basket 55, adjacent the upper end of the inner wall 56, for limited rocking motion, as by a bushing 61 of rubber or the like.

For balancing purposes, there is affixed to the shaft 59, below the container 55, a dish-shaped receptacle 62 having an in-turned upper wall 63 which defines an annular trough 64 into which an annular displacement member 65 projects. The displacement member 65 is fixed to the bottom wall 58 of the basket 55. A quantity of liquid 66 is maintained in the receptacle 62, the liquid lying in the bottom, as shown in Fig. 5,

when the device is at rest. When the device is rotating, the liquid 66 is thrown out into the annular trough 64 by centrifugal force, and is evenly distributed so long as the basket 55 is empty or contains a balanced load. However, if the container 55 contains an unbalanced load, the latter develops a centrifugal force which rocks the basket about the bearing 61, causing the displacement member 65 to displace liquid from the trough 64 on the side adjacent the greatest load, the displaced liquid flowing to the opposite side of the trough until the centrifugal force of the unbalanced liquid develops a moment about the bearing 61 equal and opposite to the moment developed by the unbalanced load in the basket 55.

The structure shown in Fig. 6 differs from that shown in Fig. 5 only in that its balancing liquid is confined in an annular flexible tube. The corresponding elements in Fig. 6 bear the same reference numerals as shown in Fig. 5, with the suffix "a." It will be observed that the balancing liquid 66a is contained within a rubber tube 67 which is positioned between the reentrant wall 63a of the receptacle 62a and the displacement member 65a that is secured to the basket 55a. The operation of the arrangement shown in Fig. 6 is identical with that of the arrangement shown in Fig. 5, except that the balancing liquid 66a is always retained within the annular trough 64a by the rubber tube 67, and displacement of the liquid 66a in response to an unbalanced load is produced by pressure of the displacement element 65a against the tube 67.

All of the modifications shown have the advantage of simplicity and ruggedness, in addition to the advantage of adequately compensating for relatively large unbalanced loads.

Although for the purpose of explaining the invention, certain specific forms of apparatus incorporating it have been described in detail, the invention is broadly applicable to many other specific forms of apparatus and it is therefore to be limited only to the extent set forth in the appended claims.

I claim:

1. A device of the type described comprising: a rotatable body and means supporting it for rotation about a predetermined axis and for swinging movement about a center located in

5

said axis; an axially symmetrical receptacle concentric with respect to said predetermined axis and axially displaced from said center and rotatable with said body, said receptacle comprising an annular channel open on its inner side and adapted to retain a ring of liquid by centrifugal force during rotation; and an annular member secured to said body and extending into said annular channel during rotation of said device.

2. A device as described in claim 1 including a closed flexible annular tubular container in which said liquid is contained, said tubular container being supported in said annular channel and being contacted by said annular member secured to said body.

3. A device of the type described comprising: an outer member rotatable about an axis and having a peripheral wall symmetrical about said axis; means for rotating said outer member; an inner member having a peripheral wall positioned within the peripheral wall of said outer member, said inner member being supported within said outer member for lateral movement with respect thereto; a first flexible annular wall interconnecting the lower edges of said inner and outer peripheral walls; a second flexible annular wall interconnecting the upper edges of said inner and outer peripheral walls; said flexible annular walls cooperating with said peripheral walls to define therebetween an annular chamber for retaining a liquid between said peripheral walls during rotation of said device, whereby the pressures developed in said liquid by centrifugal force react on said inner wall, and the lateral movement of said inner wall out of concentric relation to said outer wall displaces liquid from the region where the walls are closest to the region where they are farthest apart.
